The ornamental design for a light tool, as shown and described.

DESCRIPTION

FIG. 1 is a first perspective view of a first embodiment of a light tool embodying our design;

FIG. 2 is a first side view of the light tool of FIG. 1;

FIG. 3 is a second side view of the light tool of FIG. 1;

FIG. 4 is a front view of the light tool of FIG. 1;

FIG. 5 is a rear view of the light tool of FIG. 1;

FIG. 6 is a top view of the light tool of FIG. 1;

FIG. 7 is a bottom view of the light tool of FIG. 1;

FIG. 8 is a second perspective view of the light tool of FIG. 1; and,

FIG. 9 is a third side view of the light tool of FIG. 1.

The broken lines show portions of the article not claimed and form no part of the claimed design.
